UNITED STATES PATENT OFFICE.

ELVIN THOMPSON AND LEO L. DIEBEL, OF ALLIANCE, OHIO.

JACK.

Application filed May 5, 1924. Serial No. 711,258.

To all whom it may concern:

Be it known that we, ELVIN THOMPSON and LEO L. DIEBEL, citizens of the United States, residing at Alliance, in the county of 5 Stark and State of Ohio, have invented certain new and useful Improvements in Jacks, of which the following is a specification.

This invention relates to lifting mechanisms and the primary object of the invention is to provide a vehicle jack of a small and compact structure which can be extended a relatively great distance for permitting the lifting of the vehicle to a maximum height with a minimum amount of energy or exertion.

Another object of the invention is to provide a vehicle jack embodying stationary supporting rack bars, a main movable rack bar, a traveling casing mounted upon the stationary rack bars, and novel means for synchronously operating the casing or the stationary rack bars and sliding the main rack bar within the casing.

A still further object of the invention is 25 to provide an improved jack of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, in which drawings:

Figure 1 is a side elevation of the improved jack showing parts thereof broken away and in section,

Figure 2 is a vertical section through the 40 jack taken on the line 2—2 of Figure 1,

Figure 3 is a detailed vertical section taken on the line 3—3 of Figure 4,

Figure 4 is a section similar to Figure 2 illustrating the main lifting rack bar and 45 the housing in their partially raised position, and

Figure 5 is an enlarged fragmentary section showing the pin and groove connection between the rack bars and the housing for 50 limiting the movement between the rack bars and housing or casing.

Referring to the drawings in detail, wherein similar reference characters designate corresponding parts throughout the 55 several views, the letter A generally indicates the improved jack, which comprises a

base plate 10 formed of any desired material, such as cast iron or the like. The upper face of the base block 10 is provided at spaced points with a pair of sockets 11 and 12 which are adapted to receive the lower end of the supporting rack bars 13 and 14. As shown these rack bars 13 and 14 are disposed in spaced parallel relation and are provided with rack teeth on one edge of 60 the same. These supporting rack bars 13 and 14 are adapted to slidably receive the casing 15 which is divided by longitudinally extending spaced partition walls 16 into side guides 17 and 18 for receiving the supporting rack bars 13 and 14 and into an intermediate relatively large guide 19 for receiving the main lifting rack 20. This main lifting rack 20 is provided at its upper end 65 with a head 21 which is preferably serrated or otherwise roughened to form means for engaging the work to be lifted. One side of the casing 15 has formed thereon in any desired way housings 22 and 23 for receiving upper and lower worm wheels 24 and 25. 70 These worm wheels 24 and 25 are keyed or otherwise secured respectively to upper and lower driven shafts 26 and 27. These driven shafts 26 and 27 are arranged at right angles to the main drive shaft 28 which 75 extends forwardly from the jack A. This main drive or operating shaft 28 has formed thereon or secured thereto in any desired way a worm 29 which is adapted to mesh with the worm wheels 24 and 25. 80

The upper shaft 26 has formed thereon or secured thereto in any desired way a pinion 30 which is adapted to mesh with the main lifting rack bar 20.

The lower shaft 27 has formed thereon or otherwise secured thereto at spaced points pinions 31 which fit in the guide ways 17 and 18 and mesh with the supporting rack bars 13 and 14.

The outer end of the operating or drive shaft 28 is polygonal shaped in cross section as at 32 for the reception of an operating crank or the like (not shown), whereby the said shaft can be conveniently operated by 100 the hand of the operator.

In order to limit the upward movement of the main lifting rack bar 20 a pin 33 is secured to the lower end of the said rack bar 20 and is slidably mounted in a guide groove 34 formed in the housing 15. It is obvious 110 that when the main lifting rack bar 20 is raised to its extreme uppermost position

that the pin 33 will be at the end of the groove 34 and in engagement with the end wall thereof and thus effectively prevent further raising of the rack bar and prevent 5 the rack bar from coming out of mesh with its pinion.

In operation of the improved jack it is evident that upon rotation of the main operating or drive shaft 28 that the driven 10 shafts 26 and 27 will be operated in opposite directions and that the upper shaft will serve to lift the main rack bar 20 while the lower shaft 27 will serve to raise the casing 15, thus bringing about simultaneous movement of the casing and the main lifting rack bar.

From the foregoing description, it can be seen that we have provided an improved jack of an exceptionally simple and durable 20 construction which can be operated simply and efficiently with a minimum amount of energy.

Changes in details may be made without departing from the spirit or the scope of 25 this invention, but:

What we claim as new is:

1. A jack comprising a base plate, a pair of spaced supporting rack bars, a casing slidably mounted on the rack bars, a lifting 30 rack bar slidably mounted in the casing intermediate the first mentioned lifting rack

bars, an upper and lower driven shaft, a pinion carried by the upper shaft engaging the lifting rack bar, pinions carried by the lower shaft engaging the supporting rack 35 bars, and a single operating shaft for driving the driven shafts synchronously and in opposite directions.

2. A jack comprising a pair of spaced supporting rack bars, a casing slidably 40 mounted upon the supporting rack bars, a lifting rack bar slidably mounted in the casing between the first mentioned rack bars, gear housings formed on the casing, upper and lower driven shafts rotatably mounted 45 in the casing, a pinion carried by the upper shaft engaging and meshing with the lifting rack bar, a pair of pinions carried by the lower shaft engaging and meshing with the supporting rack bars, worm wheels secured 50 to the shafts and rotatably mounted in said gear housings, a drive shaft, and a worm carried by the drive shaft which meshes with said worm wheels.

In testimony whereof we affix our signatures in presence of two witnesses.

ELVIN THOMPSON.
LEO L. DIEBEL.
